UNITED STATES PATENT OFFICE.

HOMER LOUIS OLIPHANT, OF CINCINNATI, AND ASBURY F. MOOD, OF BUENA VISTA, INDIANA.

THILL-COUPING.

SPECIFICATION forming part of Letters Patent No. 624,525, dated May 9, 1899.

Application filed March 2, 1899. Serial No. 707,471. (No model.)

To all whom it may concern:

Be it known that we, HOMER LOUIS OLIPHANT, residing at Cincinnati, in the county of Greene, and ASBURY F. MOOD, residing at 5 Buena Vista, in the county of Monroe, State of Indiana, citizens of the United States, have invented certain new and useful Improvements in Thill-Couplings, of which the following is a specification.

10 This invention relates to carriages and wagons, and more especially to the thill-couplings used in connection therewith; and the object of the same is to produce certain improvements on United States Patent No. 618,432, 15 issued January 31, 1899.

To this end the invention consists in the simplification of some parts, the omission of others, and the addition of novel lubricating devices, all as hereinafter more fully described and as shown in the accompanying drawings, wherein—

Figure 1 is a central longitudinal section of all the parts of this thill-coupling in operative position. Fig. 2 is a perspective detail 25 of several parts thereof disconnected from each other. Fig. 3 is an enlarged sectional detail of one oil-cup and its spring-cover.

The letter A designates the axle, which is of any approved construction and formation 30 and forms no part of the present invention.

The letter C designates the clip, which is composed of an inverted-U-shaped strap of metal 1 passing over the axle, and whose arms 2 and 3 extend downward on opposite sides 35 thereof, as usual, and are threaded for the reception of nuts 4 and 5.

The letter P designates the clip-plate, which is preferably transversely grooved, as at 10, on its upper side near its rear end, for the reception of the axle A, as usual. Forward of the transverse groove 10 the body of the plate P is bifurcated, so as to form two arms 14, extending forward from a straight vertical front wall 15, and which arms are complementary 45 of each other. Each has on its inner face an inwardly-projecting flange 16, starting from a point 17 at about the mid-length of the upper edge of the arms 14, thence extending in a curved manner around the front end of said 50 arm, thence continuing to the rear along the lower edge of the arm, and terminating at a

point 18 on said lower edge somewhat in rear of the point 17. The entire plate, its arms, and flanges are preferably formed in one piece of metal.

The plate P (shown in Fig. 2) is of slightly-different construction, omitting the groove 10 and clip entirely; but as this device is applicable to many other uses than specifically as a thill-coupling we reserve the right to alter the construction of parts, as may be necessary. For instance, the device can be used for the pivot of the knife-head of a mowing-machine or of the shaker-arms of a threshing-machine. Hence where we speak of "clip-plate" herein we mean one member, and where we speak of "thill-iron" we mean the other member, which is coupled to the first by our improved means.

The letter B designates the block, which in the present instance is also preferably made of metal instead of rubber or some soft or yielding material, as hitherto common in antirattlers. This block has a flat upper face 20, a flat but rearwardly-inclined rear face 21, forming an obtuse angle 22 with the upper face, and a front face which extends vertically downward for a short distance, as at 23, and is slightly grooved, as at 24, thence makes a rearwardly-curved bearing 25, and finally extends again vertically downward, as at 27, all as best seen in Fig. 1. In front elevation this block is substantially plus-shaped, as best seen in Fig. 2, the head of the plus consisting of that portion comprising the vertical front face 23, the bearing 25 occupying the entire lateral width of the front face of the shank, and the lower end or remaining portion of the plus beneath the bearing 25 comprising that portion occupied by the vertical part 27 of the front face. This block is of much simpler construction than that hitherto employed in the patent referred to, and yet experience has shown us that we gain equal or better advantages.

The letter W designates a wedge having a vertical rear face 40 and an inclined front face 41, and in the center of the upper end of this wedge is an upright hole 42, from which leads a shallow groove 43 to and out through said rear face 40.

Instead of the spring heretofore employed

we make use of the following construction, which we find cheaper and more efficacious:

5 S is a screw or bolt threaded at its lower end and having at the upper end of its body a forwardly-projecting rigid arm 50, at whose front end is a downwardly-extending rigid teat 51, and 52 is the square or angular nut for this bolt.

H is an upright hole through the body of 10 the plate P, just in the rear of the wall 15, which hole at its upper end 60 is of a size to closely receive the body of the screw, below which it is enlarged, as at 61, forming a downwardly-facing shoulder 62 at the upper end 15 of a chamber which contains a coiled expansive spring 63, surrounding the body of the screw, and below this chamber in turn the hole is still further enlarged and squared at 65 to receive the nut 52 to prevent its rotation and yet to permit it to have a certain vertical play.

T designates the T-head at the rear end of an ordinary thill-iron, which head is bored longitudinally, as at 70, and 71 are two fine 25 ducts leading from this bore obliquely upward and coming out at the upper side of said head near its ends. There are preferably two of these ducts, although one may suffice.

In Fig. 3 is best seen our improved lubricating device, of which there may be two to 30 coöperate with the ducts just mentioned, although one might in some cases suffice. 72 is an oil cup or duct passing through the flange 16 and preferably flaring slightly to 35 ward its upper end. 73 is a plate we preferably employ, which is secured to and flush with the upper face of this flange and has a perforation 74 registering with the duct just mentioned. 75 is a button of 40 spring metal, with one end thickened, as at 76, through which passes a screw or rivet 77, by which it is riveted to said plate, while the body of this button is provided on its under side with a convex projection 78, (which

45 may be formed by stamping, as seen in this view,) so located that when the button is turned on its pivot the resilience of its body will throw this projection into and normally close said perforation 74. In the operation 50 of this oil-cup the button is turned aside, the thill-iron raised until the two ducts 71 and 72 align, and oil is poured into the perforation 74, whence it runs down and fills the bore 70. The button is then turned back to close the 55 perforation 74 and the normal use of the device will naturally spread the lubricant to all wearing-faces. We consider this oil-cup especially useful in this connection, the more so because the block B is not of rubber or any 60 substance likely to be corroded by the oil.

In use the plate P is secured to the axle A by the clip C or is connected with one member in any suitable manner. The T-head at the rear of the thill-iron (or other member) is 65 then passed downward between the arm 14 of the plate P and drawn forward. The block B is then dropped into place on the lower

sides of the flanges and moved forward until its bearing 25 rests against the rear of the T-head. The wedge W is then brought into play 70 and inserted from above with its flat rear face 40 against the front wall 15 and its inclined front face 41 against the inclined rear face 21 of the block, and this wedge is borne downward until it pinches between the block and 75 the rear wall of the plate. The screw S is then dropped into the hole H, the spring 63 inserted from beneath, and the nut 52 applied and screwed onto the thread as far as possible. Pressure on the lower face of the nut 80 then compresses the spring between it and the shoulder 62 and raises the screw, so that its arm 50 and teat 51 are entirely clear from the top of the wedge. The screw is then turned by hand as far as possible, and on releasing pressure beneath the nut the spring causes the screw to descend until the teat enters the hole 42 and the arm stands within the notch or groove 43 in the wedge W. It will be obvious that the normal tendency of 90 the spring is to draw the wedge downward, and such movement of the latter necessarily forces the block forward, so that its bearing 25 presses firmly against the rear of the thill-iron, thus silently, constantly, and effectively 95 producing a frictional antirattler composed entirely of metal and which not only takes up the wear of parts, but will not yield in the least when the vehicle is backed.

All the parts are of the desired sizes, proportions, and materials, but preferably metal. It is obvious that the groove 43 might be omitted and the teat made longer or the teat omitted and the groove made deeper. It will be clear that the parts described in connection with the screw serve in the nature of a nut-lock to prevent the accidental loss of the nut no matter how loose on the screw. As the parts wear the screw is evidently given an occasional revolution into its nut in the 100 manner above described.

The removal of parts for the purpose of cleansing or for repair will be done in an obvious manner not necessary to describe; but we might suggest that in the event of excessive wear a thicker wedge will eventually have to be employed.

What we claim as new is—

1. In a thill-coupling, the combination with a clip-plate having front side arms with inwardly-projecting flanges curved around their front ends, and a block adapted to pass between them and formed with a transverse bearing complementing that within said flanges, the plate between its arms having a vertical front wall and the rear face of said block being inclined; of a wedge having a vertical rear face and an inclined front face and adapted to fit between the arms and in rear of the block, a spring-actuated member moving in an upright hole in the plate, and a rigid arm thereon pressing normally downward upon the upper end of the wedge, as and for the purpose set forth.

2. In a thill-coupling, the combination with a clip-plate having front side arms with inwardly-projecting flanges curved around their front ends, and a block adapted to pass between them and formed with a transverse bearing complementing that within said flanges, the front of the plate and the rear of the block constituting a downwardly-tapering opening; of a wedge tapering to fit said 10 opening, a screw moving loosely in an upright hole in the plate in the rear of the wedge, a nut on the screw, a spring bearing normally downward on the nut, and an integral arm at the upper end of the screw engaging the wedge for depressing the same, substantially as described.

3. In a thill-coupling, the combination with a bifurcated clip-plate whose arms have near-wardly-facing bearings, a block therein having a complementary bearing, and a wedge behind the block, said plate having an upright hole with a small upper end, a larger chamber at its center, and a still larger squared lower end; of a coiled expansive spring with- 25 in said chamber, a square nut beneath it, a screw threaded into the nut with its body passing through the spring and out the upper end of the hole, and connections thence to the top of the wedge, as and for the purpose 30 set forth.

4. In a thill-coupling, the combination with a bifurcated clip-plate whose arms have near-wardly-facing bearings, a block therein having a complementary bearing, and a wedge 35 behind the block, said plate having an upright hole in rear of the wedge; of a screw whose body slides in said hole and whose upper end is bent forward in an arm engaging the upper end of the wedge, a nut on said 40 screw, and an expansive spring between the nut and a part of the plate, as and for the purpose set forth.

5. In a thill-coupling, the combination with a bifurcated clip-plate whose arms have near-wardly-facing bearings, a block therein having a complementary bearing, and a wedge 45 behind the block, said plate having an upright hole in rear of the wedge; of a screw whose body slides in said hole and whose upper end 50 is bent forward in an arm engaging an opening in the upper end of the wedge, a nut on said screw, means for preventing the turning of the nut, and an expansive spring between the nut and a part of the plate, as and for the 55 purpose set forth.

6. In a thill-coupling, the combination with a bifurcated clip-plate whose arms have near-wardly-facing bearings, a block therein having a complementary bearing, and a wedge 60 behind the block having a hole in its upper end and a groove shallower than the hole and leading thence to the rear face of the wedge; of a vertically-moving spring-actuated mem-

ber having an arm projecting over the block and adapted to rest in said groove and a teat 65 at its forward end adapted to stand in said hole, all as and for the purpose set forth.

7. In a thill-coupling, a combination with a bifurcated clip-plate whose arms have near-wardly-facing bearings, a block therein having a complementary bearing, and a wedge 70 behind the block having a hole in its upper end; of a vertically-moving spring-actuated member having an arm projecting over the block and a teat at its forward end adapted 75 to stand in said hole, all as and for the purpose set forth.

8. In a thill-coupling, the combination with the clip-plate bifurcated at its front end, inwardly-projecting flanges on the side arms 80 thereof curving around their front ends, a block fitting between said arms and having a transverse bearing complementing that within the curved front ends, and means for pressing this block normally to the front; of 85 a T-head on the thill-iron fitting said bearings, the head being bored longitudinally and provided with ducts extending obliquely upward from such bore, and oil-cups in said flanges adapted to register with the ducts 90 when the shank of the T is raised, substantially as and for the purpose set forth.

9. In a thill-coupling, the combination with the clip-plate bifurcated at its front end, inwardly-projecting flanges on the side arms 95 thereof curving around their front ends and extending partially to the rear at their upper edges, a block fitting between said arms and having a transverse bearing complementing that in the front ends of the flanges, and 100 means for pressing this block normally to the front; of a thill-iron whose head fits said bearings, an upwardly-flaring oil-cup in one of said flanges having a duct leading to the bearing, a plate over the cup and having a 105 perforation communicating therewith, and a button for closing such perforation at will, as and for the purpose set forth.

10. In a thill-coupling the combination with a clip-plate with side flanges forming front 110 bearings, the thill-iron, and a block pressing against the latter and forming the rear bearing; of an oil-cup extending vertically through one flange, a perforated plate at its upper end, a button having a thickened end pivoted 115 to said plate and a spring-body, and a projection beneath the latter adapted to close the perforation in the plate, as and for the purpose set forth.

In testimony whereof we affix our signatures in presence of two witnesses.
